(57) **CLAIM**

The ornamental design for an ice cream maker, as shown and described.

DESCRIPTION

FIG. 1 is a top right perspective view of an ice cream maker showing our new design.

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is bottom plan view thereof.

The broken lines in the figures are for illustrative purposes only and form no part of the claimed design.

1 Claim, 6 Drawing Sheets
